(57) **CLAIM**

The ornamental design for an antenna, as shown and described.

DESCRIPTION

FIG. 1 is a perspective view of an antenna having an end piece, showing my new design, where the end piece is positioned in line with the remainder of the antenna.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof, shown enlarged at 4x magnification.

FIG. 7 is a bottom plan view thereof, shown enlarged at 4x magnification.

FIG. 8 is a perspective view of the antenna, where the end piece is positioned at a 90-degree angle with respect to the remainder of the antenna.

FIG. 9 is a front elevational view thereof.

FIG. 10 is a rear elevational view thereof.

FIG. 11 is a right side elevational view thereof.

FIG. 12 is a left side elevational view thereof.

FIG. 13 is a top plan view thereof, shown enlarged at 4x magnification.

FIG. 14 is a bottom plan view thereof, shown enlarged at 4x magnification.

FIG. 15 is a perspective view of the antenna, where the end piece is positioned at a 135-degree angle with respect to the remainder of the antenna.

FIG. 16 is a front elevational view thereof.

FIG. 17 is a rear elevational view thereof.

FIG. 18 is a right side elevational view thereof.

FIG. 19 is a left side elevational view thereof.

FIG. 20 is a top plan view thereof, shown enlarged at 4x magnification; and,

FIG. 21 is a bottom plan view thereof, shown enlarged at 4x magnification.

The broken dot-dash lines in the figures depict a boundary of the claim that forms no part of the claimed design.
